242,317

COMBINED DESK AND LIGHT THEREFOR

Ernest Hofmann Igl, 9-11 Marienburgerstr.,
8200 Rosenheim-Mitterfeld, Germany

Filed Nov. 1, 1974, Ser. No. 520,144

Claims priority, application Germany May 2, 1974;
May 8, 1974

Term of patent 7 years

Int. Cl. D6—04

U.S. Cl. D6—162

FIG. 1

FIG. 2

FIG. 3

FIG. 4

FIG. 5

FIG. 1 is a front view of a desk from the left-hand side showing three drawers with a lamp post and the working plate fitted into place;

FIG. 2 is a view similar to FIG. 1 with the original holder drawn up;

FIG. 3 is a front view with the top drawer swung open, showing a waste paper basket on the right-hand side plus equipment with cut-outs to receive books and the like and with the working plate removed and the original holder drawn up;

FIG. 4 is a view from the left-hand side of the desk with the working plate removed and showing the lamp pole serving as a hinge rod for the drawers; and

FIG. 5 shows the bulged right side of the desk and the rear side thereof with a recessed space to shelve books or the like.

I claim:

The ornamental design for a combined desk and light therefor, as shown.
